UNITED STATES PATENT OFFICE.

NESTOR FRERE, OF LONDON, COUNTY OF MIDDLESEX, ENGLAND.

DESIGN FOR A MEDAL.

SPECIFICATION forming part of Design No. 17,843, dated November 1, 1887.

Application filed September 12, 1887. Serial No. 249,498. Term of patent 3½ years. Registered in England January 11, 1887, No. 65,340.

To all whom it may concern:

Be it known that I, NESTOR FRERE, a subject of the Queen of Great Britain and Ireland, residing at No. 13 Upper Westbourne Terrace, London, in the county of Middlesex, England, have invented and produced a new and original Design for a Medal, of which the following is a specification, reference being had to the accompanying drawings, which form a part thereof, and in which—

Figures 1 and 2 represent, respectively, the obverse and the reverse of the medal.

The plain surface *a* of the medal is bounded by a raised edge, *b*, which nearly surrounds it. It stops, however, at *c*, which is a raised edge surrounding an extension, *d*, of the medal, which extension has a perforation, *e*, formed in it, and by means of which the medal can be conveniently suspended by a ribbon or equivalent device from the neck or from the coat or vest of the wearer.

The raised edge *c* of the extension *d* represents the front wall of a bastion, and the rearward continuations *ff* of said edge the flanks of the bastion.

The perforations *gg* represent the lakes of the country—*i. e.*, Egypt.

The obverse of the medal has a symbolical Egyptian face flanked by triangular drawings, and which latter represent the steps of the great pyramid. The reverse of the medal bears a representation in relief of the head and bust of a native Egyptian or fellah.

I claim—

The design for a medal herein shown and described, the same consisting of a perforated enlargement of the medal surrounded by a raised edge to represent a bastion, perforations in the medal, an Egyptian face with two triangular drawings representing the steps of the great pyramid, and on the reverse the head and bust of a fellah.

In witness whereof I have hereunto set my hand, in the presence of two witnesses, this 7th day of April, 1887.

NESTOR FRERE.
